UNITED STATES PATENT OFFICE.

ETHAN I. DODDS, OF PITTSBURGH, PENNSYLVANIA, ASSIGNOR TO FLANNERY BOLT COMPANY, OF PITTSBURGH, PENNSYLVANIA.

STAYBOLT STRUCTURE.

1,385,779.

Specification of Letters Patent. Patented July 26, 1921.

Application filed July 29, 1919. Serial No. 314,086.

To all whom it may concern:

Be it known that I, ETHAN I. DODDS, a citizen of the United States, and resident of Pittsburgh, in the county of Allegheny and State of Pennsylvania, have invented certain new and useful Improvements in Stay-bolt Structures; and I do hereby declare the following to be a full, clear, and exact description of the invention, such as will enable others skilled in the art to which it appertains to make and use the same.

This invention relates to improvements in staybolt structures for steam boilers and more particularly to means for connecting the rounded head of a staybolt with the outer boiler sheet and permanently inclosing said head and its seat.

The object of my present invention is to provide a simple and efficient structure wherein a section of sleeve or bushing threaded through the boiler sheet may be utilized as a bearing member for the head of a staybolt, and to inclose the head of the bolt and its bearing member by a closure rigidly united at its edge directly to the boiler sheet.

With this and other objects in view, the invention consists in certain novel features of construction and combinations of parts as hereinafter set forth and pointed out in the claim.

The accompanying drawing is a sectional view illustrating an embodiment of my invention.

1 represents a portion of a boiler sheet having an opening 2, the wall of which is threaded to receive a threaded bearing sleeve section 3. The sleeve is made interiorly with a concave seat 4 for the rounded head 5 of a staybolt 6, and a portion 7 of the bore of the sleeve is made tapering to permit lateral play of the bolt. The staybolt may have a tell-tale bore 8 which may extend from the inner end of the bolt to the headed outer end, said bore being made to terminate within the head 5 of the bolt. A slot or recess 9 may be provided in the head 5 for the reception of a suitable tool whereby

the inner end of the bolt may be screwed through a suitable hole in the inner boiler sheet.

The head of the bolt may project outwardly beyond the plane of the outer face of the boiler sheet and as the tell-tale bore is accessible from the inner end of the bolt for testing purposes, the head 5 and bearing sleeve may be covered and inclosed by a cap or closure permanently united to the boiler sheet. Thus a cap 10 (which may be hemi-spherical in shape) is placed over the head of the bolt and is united to the metal of the boiler sheet around and preferably spaced somewhat from the opening through which the sleeve section 3 passes. The edge portion of the cap is so united to the boiler sheet as to become an integral part of the metal thereof. This is accompanied by welding the edge portion of the cap to the boiler sheet with the use of a suitable welding metal and the metal of the weld, indicated at 11, will become an integral part of the cap and of the boiler sheet.

Having fully described my invention what I claim as new and desire to secure by Letters Patent, is:

The combination with a boiler sheet having a threaded opening, of an externally threaded bearing sleeve passing through said opening and having an internal seat for the head of a staybolt, a staybolt having a headed portion entering said sleeve and mounted on the seat therein, a permanent closure consisting of a cap having its edge portion surrounding the opening in the boiler sheet and disengaged from said sleeve, said cap inclosing the bolt head mounted in said sleeve, and a weld around the edge portion of said cap and permanently uniting the latter with the boiler sheet.

In testimony whereof, I have signed this specification in the presence of two subscribing witnesses.

ETHAN I. DODDS.
